JAMES B. BOSTWICK, OF JERSEY CITY, NEW JERSEY.

LIFTING JACK.

Application filed June 29, 1920. Serial No. 392,637.

To all whom it may concern:

Be it known that I, JAMES B. BOSTWICK, a citizen of the United States, and a resident of Jersey City, in the county of Hudson and State of New Jersey, have invented new and useful Improvements in Lifting Jacks, of which the following is a specification.

The invention relates in general to lifting jacks, and more particularly to lifting jacks operated by fluid pressure.

The objects of the invention are to provide a combined fluid pressure operated jack and fluid reservoir embodying novel features of construction; to provide such a lifting jack having a hollow piston of novel construction which serves as a reservoir for the fluid under pressure; to obtain a novel construction and arrangement of passages and connections for first charging the reservoir directly with fluid under pressure, subsequently releasing a portion of the fluid from the reservoir behind the piston to elevate the same when it is desired to utilize the jack for lifting purposes, and after such use releasing the fluid pressure from behind the piston into the atmosphere to allow the piston to resume its normal position; to provide a novel valve means for so charging the reservoir and transferring the fluid therefrom, and to obtain other advantages and results as may be brought out by the following description.

Referring to the accompanying drawings, in which like numerals of reference indicate the same parts throughout the several views,

Figure 1 is a vertical longitudinal sectional view through a lifting jack embodying my invention, taken on the line 1—1 of Fig. 4, and showing the piston of the jack in its normal inoperative position;

Figure 2 is a sectional view through the cylinder of the jack, the piston and valve nipple being shown in side elevation and the piston being shown in an operative position;

Figure 3 is a top plan view of the jack;

Figure 4 is an enlarged fragmentary sectional view taken on the line 4—4 of Fig. 1, and

Figure 5 is a detail view of the jack head and an extension therefor.

In the specific embodiment of the invention illustrated by the drawings, the numeral 1 designates the cylinder of the jack which

may be constructed of any suitable material

such as steel, brass or the like, and which may be formed in any suitable manner as by casting, stamping or machining according to the size of jack desired and the purpose for which the jack is desired. In the present instance my invention has been shown embodied in a vehicle jack, and the cylinder 1 is shown as having one end thereof open and being substantially elliptical in cross-section for the purpose of providing an enlarged area for the base of the jack and also for preventing rolling of the jack when the same is laid upon its side. This elliptical formation of the cylinder also prevents rotation or twisting of a similarly formed piston 2 which is slidably mounted within the cylinder 1.

The piston 2 serves as a reservoir for the fluid under pressure by which the jack is operated, the said piston being shown as hollow in formation and having at its inner end a conventional packing ring or cup 3 which forms a tight chamber between the inner end of the piston and the cylinder. The outer end of the piston is closed in any suitable manner as by means of the cap 4 which is provided with a depending flange 5 which overlaps the edge of the cylinder to prevent dust or foreign matter from entering the cylinder. A fluid conduit pipe 6 extends longitudinally and substantially axially through the piston 2, the inner end of said pipe being threaded through the end of the piston and being clamped thereto by means of the nuts 7, the said nuts also serving with a washer 7^a to secure the packing cup 3 to the inner end of the piston. The outer end of the pipe 6 projects through the cover 4 and has threaded thereon a cap 8 which closes the outer end of the pipe 6 and serves in conjunction with a clamping nut 9 to secure the cover 4 to the outer end of the piston 2, the said clamping nut 9 also serving with a washer 9^a to secure a packing cup 10 between the cover 4 and the piston to provide a fluid tight joint. A jack head 11 is secured to the cap 8 in any suitable manner as by a thread connection as shown by Figure 1 of the drawings, the said jack head serving as a bearing surface for the axle of a vehicle. It will be obvious that the manner of closing the outer end of the piston 2 may be varied as desired, the present construction being only illustrative of one possible construction for this purpose.

The piston 2 is charged with fluid under

pressure through an inlet and valve nipple 13 which has one end thereof threaded into the cap 8 and through the side of the pipe 6, the said nipple being provided with a passage 14 opening through the outer end thereof and controlled by a conventional inwardly opening check valve 15. This valve 15 may be of any suitable construction, but in the present instance is shown as comprising a conventional tire-inflating valve 16 normally held against its seat by a spring 17 and having an outwardly projecting stem 18. A tubular duct 19 is threaded through the cover 4 of the piston into the said passage 14 in the valve nipple 13, and when the inlet valve 15 is connected to a compressed fluid supply the fluid is conducted through the passage 14 and bushing 19 into the piston reservoir 2. When it is desired to use the jack for jacking up a vehicle, the compressed fluid in the piston 2 is conveyed to the chamber 12 behind the piston through a passage 20 communicating with the passage 14 and the pipe 6, the said passage 20 being controlled by an inwardly opening check valve 21 similar in construction to the valve 15. The valve 21 is provided with a finger button 22 for opening the valve, and when the said button is pushed inwardly the valve 21 is opened to allow the compressed fluid to pass from the piston 2 into the chamber 12 as above described. When the compressed fluid is thus conveyed into the chamber 12 the piston 2 is raised thereby as indicated in Figure 2 of the drawings to jack up the vehicle in the usual way. In order to allow the piston 2 to resume its normal position and lower the vehicle, the compressed fluid in the chamber 12 is permitted to escape into the atmosphere through the pipe 6, passage 20 and a third inwardly opening check valve 23 in communication with the passage 20, the said check valve 23 being opened by pressure upon the finger button 24 thereof. The capacity of the piston reservoir 2 is preferably such as to contain sufficient fluid under pressure to operate the jack several times, and it will be seen that this is possible through the very slight movement of the piston during its operation. It will also be seen that by reason of the peculiar valve arrangement the piston reservoir can be easily charged by the attachment of any suitable source of compressed fluid to the inlet valve 15 without effecting any movement of the piston within the cylinder. When it is desired to jack up a vehicle it is merely necessary to place the jack beneath the axle of the vehicle, press the finger button 22 of the valve 21 to open the same thus allowing sufficient fluid to enter the chamber 12 to raise the piston and elevate the vehicle, and when it is desired to lower the vehicle it is merely necessary to press the finger button 24 of the outlet valve 23

to allow the fluid to escape from the chamber 12. Owing to the comparatively small passage 20 the escape of the fluid will be comparatively slow so as to gradually lower the vehicle without jerks or jars upon the same. The compressed fluid supply is thus always carried by and within the jack itself so that it is unnecessary to use a hand pump or a motor operated pump to elevate the piston each time it is desired to use the jack, as is the usual practice with the modern types of pneumatic jacks.

When the jack is to be used in connection with a vehicle the axle of which is a considerable distance above the jack head 11 when the piston 2 is in its lowermost position, a jack head extension 25 may be pivotally secured to the jack head 11 as shown in Figure 5 of the drawings so as to be swung into operative position upon the top of the jack head as shown in solid lines or thrown into inoperative position as shown in dotted lines. In the present instance this jack head extension 25 is shown as formed of a single strip of metal bent into the desired form and having one end thereof pivotally connected at 26 to an extension 27 on one end of the jack head 11, the other end of the strip being returned against the first-mentioned end and resting upon the jack head 11. This extension 25 is particularly desirable in a jack of this type where an unnecessarily long movement of the piston 2 would waste the compressed fluid and reduce the number of times which the jack could be operated by one charging of the piston reservoir 2.

While I have shown and described one possible embodiment of my invention, it will be obvious that many modifications and changes can be made in the construction thereof without departing from the spirit or scope of the invention, and I do not desire to be limited in the construction and use of my invention except as required by the following claims when construed in the light of the prior art.

Having thus described the invention, what I claim is:

1. In a lifting jack, the combination of a cylinder having a reservoir for fluid under pressure within itself, a piston adapted to be operated by said fluid, a nipple secured upon said reservoir and having a main passage one end of which communicates with the cylinder behind said piston and the other end of which is adapted to be connected to a fluid pressure supply, said main passage also communicating intermediate its ends with a passage leading to said reservoir, a valve in said main passage between said last mentioned passage and the said cylinder behind said piston to permit fluid pressure from said reservoir to enter said cylinder to operate said piston, and a second valve for per-

mitting the exhaust of said fluid pressure from said cylinder.

2. In a lifting jack, the combination of a cylinder having a reservoir for fluid under pressure within itself, a piston adapted to be operated by said fluid, a nipple secured upon said reservoir and having a main passage one end of which communicates with the cylinder behind said piston and the other end of which is adapted to be connected to a fluid pressure supply, said main passage also communicating intermediate its ends with a passage leading to said reservoir and having a by-pass between said last mentioned passage and said reservoir communicating with the atmosphere, a valve in said main passage between said last mentioned passage and the said cylinder behind said piston to permit fluid pressure from said reservoir to enter said cylinder to operate said piston, and a second valve in said by-pass to release the fluid pressure in said cylinder into the atmosphere.

3. In a lifting jack, the combination of a cylinder, a piston in said cylinder and having a reservoir for fluid under pressure therein, a conduit extending through said reservoir and having one end thereof communicating with the cylinder behind the piston, a main passage one end of which communicates with the said conduit and the other end of which is adapted to be connected to a fluid pressure supply, a valve for preventing escape of fluid from said supply connection, a second passage communicating with said first mentioned passage and said reservoir, a valve in said first mentioned passage between said second mentioned passage and the said conduit to control the flow of fluid pressure from said reservoir into said conduit, and a valved outlet for the fluid pressure in said cylinder behind the piston.

4. In a lifting jack, the combination of a cylinder, a piston in said cylinder and having a reservoir for fluid under pressure therein, a conduit extending through said reservoir and having one end thereof communicating with the cylinder behind the piston, a main passage one end of which communicates with the said conduit and the other end of which is adapted to be connected to a fluid pressure

supply, a valve for preventing escape of fluid from said supply connection, a second passage communicating with said first mentioned passage and said reservoir, a valve in said first mentioned passage between said second mentioned passage and the said conduit to control the flow of fluid pressure from said reservoir into said conduit, a by-pass communicating with said main passage and the atmosphere between said conduit and said second mentioned valve, and a third valve in said by-pass for controlling the exhaust of the fluid pressure in said cylinder into the atmosphere.

5. In a device of the character described, the combination of a cylinder having a reservoir for fluid under pressure arranged within itself, a piston in said cylinder adapted to be operated by said fluid, said reservoir being normally out of communication with said piston, a nipple having a passage therein adapted to be connected to a fluid pressure supply, said passage being also adapted to communicate with said reservoir and the atmosphere, an outwardly closing check valve preventing escape of the fluid through said supply connection, a valve controlling communication between said reservoir and said cylinder behind the piston, and a valve for permitting escape of said fluid behind the piston through said passage into the atmosphere.

6. In a lifting jack, the combination of a cylinder, a piston in said cylinder and having a reservoir for fluid under pressure therein, said piston having an inner head, a cover on the outer end of said piston, a pipe extending longitudinally through said piston and having its ends threaded into said inner head and said cover, one end of said pipe projecting beyond said cover, and the other end opening into the cylinder behind said piston, a cap threaded on the outer end of said pipe to clamp the said cover on said piston, a nipple secured upon said cap and having a passage communicating between the said reservoir in the piston and said pipe, a valve controlling said passage, and means for exhausting the fluid pressure in said cylinder into the air.

JAMES B. BOSTWICK.
